Primary Examiner—Joel A. Sincavage*Assistant Examiner*—T. Chase Nelson*(74) Attorney, Agent, or Firm*—Michael P. Leary; Charles E. Yocum; Adan Ayala(57) **CLAIM**

The ornamental design for an impact driver, as shown and described.

DESCRIPTION

FIG. 1 is a right front perspective view of an impact driver showing a first embodiment of my new design.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

The broken lines and the areas within the broken lines form no part of the claimed ornamental design.
